Specification for Design.

Patented June 18, 1918.

Application filed April 20, 1918. Serial No. 229,865. Term of patent 14 years.

To all whom it may concern:

Be it known that I, CHARLES J. HODGES, a citizen of the United States, resident of Elyria, in the county of Lorain, State of Ohio, have invented a new, original, and ornamental Design for Vehicle-Tires, of which the following is a specification, reference being had to the accompanying drawing, forming part thereof.

In the accompanying drawing:

Figure 1 represents an elevation of a sec-

tion of vehicle tire showing my improved design; Figs. 2 and 3 represent sections taken in the planes indicated by the lines, II—II, III—III, respectively, Fig. 1.

I claim:

The ornamental design for a vehicle tire, substantially as shown.

Signed by me, this 17th day of April, 1918.

CHAS. J. HODGES.
